UNITED STATES PATENT OFFICE.

LOUIS J. HERTLIN, OF WOODHAVEN, NEW YORK.

PRODUCTION OF ALUMINUM PRINTING PLATES.

Application filed April 23, 1923. Serial No. 634,180.

To all whom it may concern:

Be it known that I, LOUIS J. HERTLIN, a citizen of the United States, and a resident of Woodhaven, county of Queens, and State of New York, have invented certain new and useful Improvements in the Production of Aluminum Printing Plates, of which the following is a specification sufficient to enable those conversant with the art to which

10 the invention appertains to utilize the same.

While applicable to the preparation of aluminum printing plates generally, my improved method of treatment is designed more particularly for use in the production 15 of aluminum plates for "poster" printing, so called, either in one or a plurality of colors, whereby more satisfactory and economical results are attained than heretofore, substantially in the manner hereinafter 20 fully set forth, and claimed specifically.

In the accompanying drawings I illustrate a practical embodiment of the essential features of my invention, although I do not limit myself to the identical method or 25 sequence of steps in the process of production shown by way of exemplification, since modifications may be resorted to in minor details with equivalent results, and without departing from the spirit and intent of my 30 invention in this respect.

With this understanding, and it being further understood that the dimensions indicated are not arbitrary, and may be varied according to requirements;

35 Fig. 1, represents a face view of the artist's original sketch;

Fig. 2, the original sketch as marked off into subdivisional sections;

40 Fig. 3, a half-tone print of Fig. 2 on plate of miniature size;

Fig. 4, an impression on glass from the hand corrected miniature plate shown in Fig. 3;

45 Fig. 5, the sections of the poster segregated and enlarged from miniature negatives of the plates ready for printing from; and

50 Fig. 6, the resultant sheet poster printed sectionally from the enlarged plate shown in Fig. 5; and positioned on poster board or surface in complete and correct co-relation.

In carrying out my invention in its simpler form, as applied to the production of a one color aluminum printing plate of relatively small size for use alone, an original copy 1 or design of minimum size is pre-

pared, and when approved, a photographic negative is obtained thereof, from which negative a positive half tone print is made on a sensitized aluminum plate 2 through 60 the medium of a suitable screen, in a manner well known in the art of photography. This half tone aluminum key plate 3 is re-touched by hand and then etched, the etched key plate being then ink-rolled, and an impression there-of taken on glass, yielding a positive from which a negative is prepared, which is used in an enlarging camera for the production on an aluminum plate of suitable area, of a positive reproduction of the 70 desired degree of enlargement as compared with the original miniature of design first referred to. The full size aluminum printing plate is then etched and prepared for the press in the usual way.

Where more than one color is to be used in the production of the design, the process is the same up to and including the half tone production on the aluminum key plate for retouching, with this exception,—that 80 this half tone aluminum key plate is reproduced for each color to be used, so as to afford means of correction for each color plate separately, when the process proceeds, as above exemplified, for each color plate.

When co-related plural sectional aluminum printing plates are essential, owing to the relatively large size of the poster to be provided for, i. e., where the inclusion of the design on one plate would be impractical or undesirable, as in the case of posters intended to cover large areas, the subdivision is effected in the enlarging camera, where separate plates are used for prescribed subdivisions of the original design.

90 Thus, in this method of preparing the full sized sectional printing plates, the original miniature design is marked to indicate the lines of subdivision, such as 1^a 1^b 1^c 1^d 1^e and the appropriate portions of the separate 100 plates (including color plates, if any) obtained from said retouched halftone aluminum key plate, are segregated and exposed individually in the enlarging camera to produce the desired enlarged sectional printing plates for the unitary design,—each resultant plate being etched and prepared for the press as heretofore.

105 My method of production of aluminum printing plates enables me to effect retouching and correction of the work on a small scale, as compared with the old art of re-

touching and correcting each full sized plate directly and individually prior to etching, etc.

This means greater accuracy and uniformity in tone in the final production, as well as economy in time and labor, especially in color work, and sectional poster work. In other words, my process affords the great practical advantage of being able to prove the plates and make sure that they are absolutely correct before proceeding with the enlargement. Furthermore, the lengthy and tedious finishing of the enlarged plate by artist hand work, etc., is eliminated.

15. What I claim as my invention and desire to secure by Letters Patent is,

1. The method herein set forth of producing aluminum printing plates, consisting in preparing an original design in miniature, 20 making a photographic negative thereof, printing a half tone positive therefrom on a sensitized aluminum plate, retouching by hand the aluminum key plate thus attained, etching said aluminum key plate, ink-rolling 25 said key plate and imposing an impression thereof on glass, using said positive print on glass for the making of a negative and using said negative in an enlarging apparatus to transfer the design to a sensitized aluminum plate which is then developed, etched, and preparatory for use in the press, substantially in the manner and for the purpose described.

2. The method herein set forth of producing aluminum printing plates for color work, consisting in preparing an original design in miniature, making a photographic negative thereof, printing a half tone positive therefrom on a sensitized aluminum plate, retouching by hand the aluminum key plate thus attained, etching said aluminum key plate, ink-rolling said key plate and imposing an impression thereof on glass, using said positive print on glass for the making of a negative for each color included in the design, correcting each of said negative color plates, and using said negative color plates in an enlarging apparatus

to transfer the design to sensitized aluminum plates which are then developed and etched preparatory for use in the printing press, substantially in the manner and for the purpose described.

3. The method herein set forth of producing sectional poster aluminum printing plates, consisting in preparing an original design in miniature, indicating thereon the requisite sectional subdivisions thereof, making a photographic negative of the miniature design thus prepared, printing a half-tone positive from said negative on a sensitized aluminum plate, retouching by hand the aluminum key plate thus attained, etching said aluminum key plate, ink-rolling said key plate and imposing an impression thereof on glass, using said positive print on glass for the making of negatives, and using said negatives in an enlarging apparatus to transfer the design to sensitized sectional aluminum printing plates which are then developed, etched, and prepared for use in the press, substantially in the manner and for the purpose described.

4. The method herein set forth of producing sectional color poster aluminum printing plates, consisting in preparing an original design in miniature, indicating thereon the requisite sectional subdivisions thereof, making a photographic negative of the miniature design thus prepared, printing a halftone positive from said negative on a sensitized aluminum plate, retouching by hand the aluminum key plate thus attained, etching said aluminum key plate, ink-rolling 75 said key plate and imposing an impression thereof on glass, using said positive print on glass for the making of negatives, one for each color included in the design, and using said negatives in an enlarging apparatus to transfer the design to sectional sensitized aluminum printing plates which are then developed, etched, and prepared for use in the press, substantially in the manner and for the purpose described.

LOUIS J. HERTLIN.
